CLAIM

The ornamental design for an holder for flags or the like, as shown and described.

DESCRIPTION

FIG. 1 is a front left perspective view of a holder for flags or the like showing my new design, the flags shown in broken lines for illustrative purposes only;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and

FIG. 7 is a bottom plan view thereof.
